(57) **CLAIM**

The ornamental design for a cup cover, as shown and described.

DESCRIPTION

FIG. 1 is a back, left, top perspective view of a cup cover showing my new design;

FIG. 2 is a front, right, bottom perspective view thereof;

FIG. 3 is a front view thereof;

FIG. 4 is a back view thereof;

FIG. 5 is a left view thereof;

FIG. 6 is a right view thereof;

FIG. 7 is a top view thereof;

FIG. 8 is a bottom view thereof;

FIG. 9 is an enlarged view of the encircled area 9 of FIG. 1; and,

FIG. 10 is an enlarged view of the encircled area 10 of FIG. 7.

The broken lines shown on the drawings depict portions of the cup cover that form no part of the claimed design. The dot-dash broken lines represent the designation of the enlargement views and form no part of the claimed design.

1 Claim, 10 Drawing Sheets
